UNITED STATES PATENT OFFICE.

JOSEPH J. SMITH, OF NEW YORK, N. Y.

HUMIDIFYING APPARATUS.

No. 835,895.

Specification of Letters Patent.

Patented Nov. 13, 1906.

Application filed May 6, 1903. Serial No. 155,823.

To all whom it may concern:

Be it known that I, JOSEPH J. SMITH, a citizen of the United States, residing at New York city, county and State of New York, have invented certain new and useful Improvements in Humidifying Apparatus, of which the following specification and accompanying drawing represent as an illustration that form of my invention which I now consider the best out of the various forms in which the principles of the invention may be embodied.

My novel arrangement of apparatus for humidifying the atmosphere of apartments, particularly those in which people are living, involves two associated devices—to wit, a humidifier with both its intake and outgo passages communicating with the compartment to be treated and an exhaust device for regulating the degree to which the passage of the air through the humidifier will be repeated. The exhaust is of smaller capacity than the humidifier and may be adjusted to any degree of capacity within its working range. By properly setting the relative capacities of the two devices for any given conditions they may be left to run indefinitely without attention, whereas without the regulating action of the exhaust the humidifier if of sufficient capacity to reach and draw through it the entire volume of air in the room, as distinguished from creating a local eddy therein, will soon oversaturate the atmosphere and render it uncomfortable.

Referring to the accompanying drawing, A represents a room or apartment of any desired size suitable for the capacity of the apparatus used.

B represents the humidifier, which is of the form shown in other pending applications for patent. It is sufficient to say that it comprises an upright casing C, within which are stretched a series of vertical absorbent sheets D, that are maintained wet by suitable moistening devices, which it is not necessary to describe.

E is a blower driven by an electric motor and serving to pass the air longitudinally along the sheets from top to bottom. The intake of air is through suitable openings F in the upper part of the casing of the humidifier, and the outflow is through similar openings G in the lower part of the casing.

H is an exhaust-blower serving to continually remove from the apartment a portion of the humidified air, being preferably placed in the upper part of the room. The blower H is arranged by its size or speed to have a smaller capacity than the blower of the humidifier which serves to circulate the air of the room through the machine.

Assuming the humidifier B to be started into operation alone, it would soon oversaturate the atmosphere beyond the degree desired; but by simultaneously setting into action the exhaust H the oversaturation is prevented, although the entire volume of air in the room may be repeatedly brought into and passed through the humidifier. The action of the exhaust in removing a portion of the air which is replaced by an equal portion of dry air entering through any suitable opening causes the air entering the humidifier to be less moist by reason of the dry air mingled therewith than would otherwise be the case. In this manner the entire atmospheric contents of the room may be kept in movement through the humidifier and all of it thoroughly moistened without becoming oversaturated. The process may also go on automatically and without attention as long as may be desired.

What I claim as new, and desire to secure by Letters Patent, is—

1. The combination in an apparatus for humidifying a room or apartment, of a humidifier communicating with the apartment at both its inlet and outlet and having means for passing air repeatedly from the apartment through the humidifier and back into the apartment, and means for expelling air from the apartment in less quantities than the flow of air through the humidifier, thereby regulating the effect of the humidifier; substantially as described.

2. The combination in an apparatus for humidifying a room or apartment, of a humidifier communicating with the apartment at both its inlet and outlet and having means for passing air repeatedly from the apartment through the humidifier and back into the apartment, and means for expelling air

from the apartment in less quantities than
the flow of air through the humidifier, there-
by regulating the effect of the humidifier,
said means consisting of an air-ejecting fan
5 communicating at its inlet end with the
apartment and discharging outside of the
apartment; substantially as described.

In witness whereof I have hereunto set my
hand, before two subscribing witnesses, this
21st day of April, 1903.

JOS. J. SMITH
